INDICATING DEVICE

Reynold B. Johnson, Binghamton, N. Y., assignor to International Business Machines Corporation, New York, N. Y., a corporation of New York

Application January 3, 1936, Serial No. 57,341

14 Claims. (Cl. 177—311)

This invention relates to devices for indicating graphically the results of counting operations.

The machine of the present invention is provided with a series of vertical adjustable tapes 5 mounted so that normally the upper ends of the tapes coincide with a horizontal datum line. Each tape is operated by a key which may be depressed one or more steps a variable number of times to move the end of the tape a differential 10 distance above the datum line. After a number of adjacent tapes are operated, a comparison may be made by observing the graph line formed by the upper ends of the tapes. The tapes are graduated with markings placed so that after 15 adjustment, a number representing the number of steps of adjustment appears at the datum line. Directly below each tape near the datum line, is an identification mark of the name, number or date represented by the tape. A reading 20 of the tape graduation at the datum line and the identification directly thereunder gives full information of the data represented by the adjusted tape.

An object of the invention is to provide means 25 for counting and indicating an accumulated value or a score.

Another object of the invention is to provide a means comprising a plurality of classified item 30 counting and indicating devices which together form a graphical indication of the variation between various classes of counted items. There are provided a series of adjustable indicating tapes each of which is separately operated and extended a distance proportional to the number 35 of items in a related class. If it is desired to record the count of a single class of items, then only one tape need be adjusted. But, if it is wished that a comparison be made between different classes of items, then a plurality of tapes are 40 adjusted to represent the count of items in the related classes.

An object of the invention is to provide a plurality of different operating means for adjusting the counting and indicating tapes. A direct positive drive and a remote electric operating control are part of the machine. A tape is adjusted 45 either by direct manipulation by key depression, by electric impulses initiated when a remote control key is depressed, or by electric impulses sent 50 automatically from a record controlled tabulating machine.

Another object of the invention is to provide a graph sheet marking and cutting guide. The upper ends of the series of adjusted tapes form a 55 guide for a marking or cutting tool bearing

against a graph sheet. The tapes may be colored in contrast with the background and a graph produced by taking a photograph of the tapes. A hole at the upper end of each tape provides a means for guiding a pencil in making vertical 5 graph lines of differential length as the tapes are moved by the pencil to indicating position or restored from indicating position to normal position.

Another object of the invention is to provide 10 means whereby two related graph figures or numbers, such as the ordinate and abscissa readings of a graph, are placed close together. In the usual graph, the two readings identifying the placement of a point on the graph line are remote 15 from each other on the left and bottom edges of the graph. In the present tape construction, the ordinate reading appearing as a graduation on the tape, is directly above the abscissa reading of the same point. There is a dual indication of 20 the ordinate reading, because in addition to the tape graduation reading, the top of the tape marks a similar reading in alignment therewith at the left of the graph.

A feature of the invention is the use of thin 25 steel tapes as counting, indicating and marking guides. The tapes are strengthened and stiffened by being formed with a curved cross-section.

The invention is illustrated by a set of drawings which form part of the disclosure. 30

In the drawings:

Fig. 1 is a front elevation view of the machine showing a series of tapes in adjusted positions in front of a sheet of cross section paper.

Fig. 2 is a side elevation view of the machine 35 showing the differential key stop and key release controls.

Fig. 3 is a sectional elevation view of the machine taken along the line 3—3 of Fig. 1.

Fig. 4 shows a graph sheet which has been cut 40 under the guidance of the adjusted tapes and placed against a background of contrasting color.

Fig. 5 shows a cross section of the curved tape.

The machine is mounted in a framework comprising base 10, side frames 11 and 12, front plates 45 13 and 14, rear plates 15 and 16, and a top plate 17.

Mounted between side frames 11 and 12, is a shaft 18 carrying a series of loosely pivoted drums 19. The periphery of each drum is curved and a 50 similarly curved thin steel tape 20 is held against the lower part of the drum by three rollers 21 cooperating with the sides and bottom of the drum 19. Three shafts 22 are mounted in the side frames carrying the loosely pivoted rollers 55

21. Shoulders 23 on the rollers guide the edges of the tape 20 so that it is held in place on the curved periphery of the drum and so that the two upwardly extending free ends of the tape are held in an exact vertical plane at right angles to the base of the machine.

As seen in Fig. 1, a plurality of such closely mounted tapes 20 are provided to project up over the front of the machine. Each tape 20 is provided with a drum 18 and a set of three guide rollers 21.

The tape 20 is formed with a curved cross section as shown in Fig. 5 so that it is strengthened and stiffened. Therefore, both of the free ends 15 of the tape remain rigidly in vertical position even when fully extended up beyond the guiding influence of rollers 21.

The forward part of each tape 20 projects up through a slot in the bottom L shaped end of front plate 13. The front end of the tape terminates in a flat shoulder 24 which may be used as a marking or cutting guide. Beneath the shoulder is a hole 25 perforated in the tape. A rapid adjustment of the tape may be made by 20 grasping the shoulder 24 and pulling the tape up to the proper position. Another method of adjustment is to insert the point of a pencil or other marking means in the hole 25 and shift the end of the tape to wherever desired and at the 25 same time make a mark of a differential length on the graph sheet under the tape.

The rear part of each tape 20 (Fig. 3) projects up parallel to and in contact with the inside of the rear plate 15. At the upper end of the tape 35 is attached a single toothed block 26 cooperating with teeth 27 cut in the side of a keystem 28 guided for vertical movement in a slot 29 in the top plate 17 and a notch in an angle iron 30 fastened between the side frames.

40 A spring 31 raises the keystem 28 until an extension 32 thereon abuts against the bottom of an adjustable rod 33. Manipulation of the button 34 at the top of the keystem will lower the keystem until the bottom end thereof strikes the flattened top of a fixed stop shaft 35 held between the side frames. Leaf springs 36 and 37 urge the keystem towards the rear so that toothed block 26 is engaged by one of the teeth 27.

As seen in Fig. 1, a plurality of keystems 28 are 50 provided, one for each tape 20. The construction and operation of the stems is uniform, so that a description of one applies to all others.

The distance that the rear end of the tape is shoved down by the depression of the key depends 55 on the normal space between the bottom of the keystem and the top of shaft 35, and that in turn depends on the position of rod 33 which holds the keystem in normal position. The location of rod 33 may be varied to confine the movement of 60 the keystem within 0-5 steps.

Attached to a shaft 38 pivoted in the side frames are a pair of arms 39 which carry the rod 33. The parts form a bail overlying the extensions 32 on all the keystems 28, said bail rocking with shaft 65 38. Outside the right side frame 11 (Fig. 2) a pointer arm 40 is fastened to the shaft 38. The pointer arm carries a knob 41 and a plunger which may be set in any one of the six holes 42 in the frame to set the rod 33 so that the operating 70 means is adapted to move the tapes a distance of 0-5 steps as indicated by the numbers under the holes 42.

With the rod 33 positioned as shown in Fig. 3, the open space between the end of the keystem 75 and the top of stop 35 is equal to five graduations

on the tape. If the keystem 28 is fully depressed, a tooth 27 on the stem engages the tooth 26 and the tape is pushed down in the rear and around the drum and up five graduations at the front of the graph machine. The friction between the 5 tape and the rear plate 15 and other parts, prevents the tape from following the keystem back upward to normal position. Spring 31 restores the keystem as soon as downward pressure is removed therefrom. Springs 36 and 37 yield on 10 the upward movement of the keystem so that teeth 27 ratchet idly over the tooth 26.

A means is provided to disengage the keystems from the tapes so that the tapes may be restored or the pointer 40 may be readjusted to give the 15 keys a new differential setting. Each keystem 28 is formed with a pair of notched shoulders 43 and 44. Cooperating with the shoulders are bars 45 and 46 fastened to shafts 47 and 48, respectively, carried by the side frames. The bars extend across the machine in association with all the keystems so that when they are operated all tapes are released. The two bars are joined for parallel movement by a link 49 which is articulated between arms 50 and 51 fastened to the 20 shafts 47 and 48 carrying the bars. Outside the right side frame 11 (Fig. 2) a restoring arm 52 is fastened to shaft 48. A knob 53 on this arm 52 may be grasped and operated to swing the arm so that a plunger thereon projects in either of two 30 holes 54 designated "in" and "out" on the plate.

When arm 52 is rocked to the left to the "out" position, shaft 48 is rocked counterclockwise and through link 49, shaft 47 is rocked a similar amount in the same direction. Then bars 45 35 and 46 bear against shoulders 43 and 44 and carry all the keystems 28 to the left against the pressure of springs 36 and 37. This serves to disengage all the teeth 27 from toothed blocks 26 to free the tapes for restoration.

The tapes 20 may be restored individually by 40 grasping a shoulder 24 or placing a pencil in a hole 25 to draw the front end of a tape down to normal position. All the tapes may be restored simultaneously by placing a ruler horizontally 45 across the top of all shoulders 24 and drawing it down to the bottom.

While the keystems are held out of engagement, the rod 33 may be adjusted to set the keystems for a different differential movement without disturbing the tapes. Pointer 40 (Fig. 2) may be 50 swung to the left into engagement with one of the holes 42 other than the hole at the extreme right. As it is moved this way, shaft 38 is rocked in a clockwise direction and arms 39 lower rod 33 55 against extensions 32 to shove the keystems 28 down nearer to shaft 35. Thereafter, depression of any key will result in a tape movement of less than five steps, the amount of movement depending on the position of pointer 40.

When restoring arm 52 is moved back to the right, into the position shown in Fig. 2, bars 45 and 46 release the keystems and permit them to be engaged again with the toothed blocks 26.

In addition to the direct mechanical methods 65 for adjusting the tapes by manipulation of shoulder 24 or button 34, other electrically controlled operating means are provided. These electrical means operate indirectly to adjust the tapes, because they actuate the keystems 28 which then 70 adjust the tapes just as though they were depressed by hand.

Attached to the inside of front plate 13 (Fig. 3) are a pair of brackets 55 carrying a pair of shafts 56 and 57. Another pair of brackets 61

carries a shaft 62. Pivoted on top shaft 56 are a series of operating levers 58, one for each key-
stem, each overlying a pin 59 on a related key-
stem 28. Pivoted on levers 58 and depending
therefrom are a series of alternately short links
60 and long links 60'. Each short link is articulated
at the lower end on an armature lever 63
pivoted on shaft 51. And each long link is connected
in a similar fashion to an armature lever
63'. Beneath armatures 63 are stationed a series
of magnets 64 supported on an angle iron 65
fastened to the inside of the front plate. Inter-
spersed between magnets 64, and below the same,
are another series of magnets 64' in alignment
with links 60' and armatures 63'. These magnets
64' are fixed on an angle iron 65' fastened to
plate 13. The staggered placement of the mag-
nets 64 and 64' is designed merely to provide more
space for the magnets than the space that would
otherwise be provided with all magnets in one line.

Whenever a magnet 64 or 64' is energized, the
associated armature lever and link is operated,
and operating lever 58 is drawn down to press
against pin 59 and depress the keystem 28. The
differential movement or adjustment of the re-
lated tape 20 is effected through teeth 27 and
movement of the keystem between stop rod 33 and
stop 35 just as when operated manually. De-
energization of the magnet releases the parts for a
restoring movement as urged by spring 31 which
brings the parts back to and holds them in the
normal position.

The magnets 64 and 64' are wired so that they
may be controlled by keys 66 (Fig. 2) remote from
the machine. There is a key 66 for each magnet
in the machine. Depression of a key closes a
pair of contacts 67 to establish a circuit through
wires 68, 69 and 72, switch 73 and the battery or
other current source 70. A cable 71 contains
all the wires leading to and from the graph ma-
chine. Wire 69 is connected to all the magnets
64 and 64' in series, and the separate wires 68,
68', 68'', etc., are each connected to a separate
related magnet 64 or 64'. Through these con-
nections it is possible to direct the adjustment
of any tape 20 from a remote point by depressing
a selected key 66 to energize the proper magnet 64.

Other wiring connections are provided to place
the graph counting and indicating device of the
present invention under the control of a record
sensing tabulating machine such as the machine
disclosed in U. S. Patent No. 2,010,653, issued
August 6, 1935, to R. Warren. At the lower right
end of Fig. 2 there is shown a portion of the
wiring diagram of Patent No. 2,010,653 and con-
nections thereto from magnets 64 and 64', the
arrangement being such that every time one of a
pair of countermagnets 170WE and 170RE are
energized, an associated graph counter magnet
64 or 64' is also energized. It is fully explained
in the patent mentioned, how examination papers
are sensed for correct responses to printed ques-
tions, and how magnet 170RE is energized once
for each correct answer and magnet 170WE is
energized for each wrong answer.

If it is desired that the adjustment of the tapes
20 be controlled automatically by the scoring ma-
chine of Patent No. 2,010,653, switch 73 is moved
to contact a wire 74 connected to a main line
70 of the machine and plug wires 75 and 76 are
connected so that a pair of magnets 64 are placed
in parallel with magnets 170WE and 170RE. Then
whenever a scoring magnet is energized, the
associated graph magnet is operated. For ex-
ample, whenever magnet 170WE is energized, the

related magnet 64 is energized by an impulse
through the parallel connections including plug
wire 75, wire 68, magnet 64, wire 68, switch 73,
and wire 74 to line 70.

Before selecting test scoring control, pointer
48 may be set to the "1" position so that each
energization of a magnet 64 raises the related
tape 20 one graduation. Thus the tapes may be
used to count and indicate the number of right
and wrong answers given by one pupil or a group
of pupils. Other classifications may be made
according to the identification of the questions,
the class of the pupil, etc., the graph indications
then showing comparisons of right and wrong
answers or comparisons of right answers by
classes or questions.

Fig. 1 is an illustration of the appearance of
the front of the machine after a series of tapes
20 have been adjusted to graph indicating posi-
tion. In this view it is seen that a sheet of
cross section paper 77 is placed behind the tapes.
The top edge of the sheet 77 is held in place by
a recessed moulding 78 fastened to the front of
the machine. The bottom edge of the sheet 77
(Fig. 3) is supported on a shoulder extending
from the front plate 13. The tops of the tapes
also serve to hold the record sheet in place be-
cause even when the tapes are in the lowest or
normal position they extend above the shoulder
on plate 13. A slanted frame 79 is fastened to
the front plates 13 and 14 and provided with an
inner channel 80 acting as a guide for an indicat-
ing strip 81. The frame 79 is cut with a series
of apertures 82 (Fig. 1) one for each tape and
in alignment therewith to show a properly spaced
number on the strip 81. As seen in Fig. 2, the
frame 79 is slotted at 83 so that strip 81 may be
easily removed and a new identification strip
entered to suit new requirements. The strip
shown in Fig. 1 identifies the tapes as represent-
ing years, starting with the year 1910.

In addition to identifying the tapes these strip
figures may represent an abscissa notation when
used to fix a point on a graph line such as the
graph line 84 (Fig. 1) which may be marked by
drawing a marking tool along the tops and down
the sides of the tapes 20. The numbers arranged
in a vertical column at the left of the machine
are the ordinate notation which may be stamped
in the frame of the machine and printed on the
border of the graph sheet. The spaces of five
units between the numbers correspond to a space
of five graduations on the tapes 20. The lowest
ordinate figure "0" is in alignment with the hori-
zontal datum line which marks the normal posi-
tion of the tops of the tapes.

After a tape 20 is adjusted, it is not necessary
to scan the ordinate numbers to determine the
extent of adjustment of the tape. All that is
required is to look directly above the abscissa
notation and observe the tape numeral or gradu-
ation in line with the datum line. For example,
the "1913" tape shows an adjustment of 45
graduations. The two related figures 1913 and
45 are close together and easily read with one
glance. This is an improvement over the usual
method of reading a graph by tracing a line up
and over in order to get the two widely separated
ordinate and abscissa readings.

Instead of marking a stepped graph line such as
line 84, an angular line may be built up by mark-
ing through the holes 25 in the tapes. If the
adjustment is controlled manually, the marking
may be done as the tapes 20 are moved up to
indicating position. However, if the tapes are 75

moved up by any of the other three key operated and automatic means, the marking of vertical graph lines by a pencil or pen extended through holes 25 may be done as the tapes are being pushed down into normal position.

When the graph sheet 11 is removed after such markings, a series of spaced vertical lines are found extending up from the datum line. The tops of these vertical lines may be joined by short 10 angular lines which together form a graph line.

Another form of graph may be made by pressing a cutting tool or knife instead of a pencil along the line 84 (Fig. 1) and thus cut out a colored graph sheet 84 (Fig. 4) which shows up in 15 a clear way when backed by a cardboard 85 of contrasting color.

An effect such as that shown in Fig. 4 may be produced in another way by taking a photograph or photostat of the front of the graph machine 20 with the tapes adjusted (Fig. 1). For such purposes the tapes 20 may be painted a solid color and the spaces between the tapes may be decreased in width or eliminated entirely by widening the tapes until their sides touch.

25 The counting and graph indicating devices disclosed herein may be controlled from a plurality of remote points by locating the keys 66 at such points, or by plugging into tabulating machines at different stations. If the capacity of one 30 graph indicator is not sufficient, a plurality of such machines may be placed side by side to extend a graph. In addition to the use for general business administration, the disclosed graph devices have utility in connection with competitive sales campaigns, production control records, 35 questionnaire analysis and many other fields of statistical work.

While there has been shown, described and 40 pointed out the fundamental novel features of the invention, it will be understood that various omissions, substitutions and changes in the form and details of the device illustrated and in its operation may be made by those skilled in the art without departing from the spirit of the invention. It is the intention therefore to be limited only as indicated by the scope of the following 45 claims.

What is claimed is:

1. In a counting device, an indicating marker 50 with a fixed datum line, a tape marked with graduations, a block on said tape, means for supporting said tape so that it is free for movement in a straight line and so that a certain graduation on said tape registers with said fixed datum line on said marker, a manipulative key and a keystem attached thereto, said keystem having teeth cooperating with the block on said tape to adjust it one or more steps according to the extent of operation of the key and the number of 55 times the key is operated so that a selected graduation on the tape registers with said datum line, and means for restoring said key and keystem.

2. In a counting device, an indicating marker with a datum line, a tape marked with graduations, a toothed block on one end of said tape, means for supporting and guiding said tape so that it is held in place but free for positive adjustment in a straight line over said marker, a manipulative key and a keystem attached thereto, said keystem being formed with ratchet teeth 60 cooperating with the block on said tape to adjust it, when the key is depressed, means for restoring said key and keystem and means for adjustably limiting the movement of the keystem so that the 65 key advances the tape a certain number of gradu-

tions beyond said datum line every time the key is depressed.

3. In a machine for comparing the count of different classes of items, an indicating marker with a datum line, a series of tapes marked with 5 graduations, one tape for each class of items, toothed blocks on said tapes, means for supporting said tapes in juxtaposition for parallel movement near said marker, a series of manipulative keys, one for each tape, and keysystems formed with 10 ratchet teeth attached to said keys for cooperating with said toothed blocks to move the related tapes through different distances from said datum line depending on the number of times said keys are operated, and means for restoring said keys 15 and keysystems after each operation.

4. In a graphic counter, a drum, a thin tape with a bent cross section on said drum with two ends of said tape extending therefrom, a series of guide rollers for holding said tape against the 20 drum and for guiding the two ends of the tape so that they project from the drum at substantially the same angle, a fixed flat plate along which one unsupported end of said tape is moved to an indicating position, and a tape moving 25 key and keystem mounted in the area between the ends of said tape for operating the other end of said tape so that said one end is moved a corresponding distance.

5. In a graph indicating and counting device, 30 a series of parallel tapes each having a tooth projection, a series of manipulative keysystems for shifting the tapes differentially, one for each tape and each provided with teeth for engaging the tooth on the related tape, an adjustable stop 35 common to all keysystems for limiting the manipulated movement thereof, means for restoring the keysystems, means for normally holding the keysystems engaged with the tapes, means common to all the keysystems for disengaging them 40 from said tapes, and means adapting the tapes to be restored to normal position.

6. In a graph indicating and counting device, 45 a series of parallel tapes marked with graduations, individual operating means for moving said tapes step by step different distances dependent on the number of times a related operating means is operated, a pair of stops common to all operating means for limiting the movement of said operating means in two directions, 50 and manipulative means for adjusting one of said stops so that the range of operation of said operating means is limited and the number of graduations that said tapes are to be moved is predetermined.

7. In a graph sheet marking device adapted 55 for control by a sheet marking pointer, a plurality of tapes mounted in juxtaposition in front of said sheet, means for supporting said tapes for parallel movement, each tape being formed with a hole, through which said pointer may be inserted to contact said sheet for marking graph lines thereon as said tapes are moved variable distances by the pointer.

8. In a graph indicating and counting device, 65 a plurality of graduated tapes mounted in juxtaposition, one end of each tape being formed with a shoulder which may be manipulated to adjust the tape, means for supporting and guiding the tapes, a plurality of keys one for each 70 tape, keysystems attached to said keys and formed with teeth cooperating with the ends of the tapes opposite to said shouldered ends to move the tapes predetermined amounts, adjustable means for limiting the amount of movement of 75

5 said keysystems, a series of magnets with connections to said keysystems for operating said tapes, pairs of contacts with circuits including said magnets, and remote control keys for closing an associated pair of said contacts to operate a related magnet the connections of which adjust a corresponding keystem and tape a predetermined amount.

9. In a graph sheet marking device adapted 10 for control by a sheet marking pointer, a plurality of tapes mounted in juxtaposition in front of said sheet, each tape being formed with a hole, means for adjusting said tapes individually variable distances, each hole acting as a guide 15 for said pointer when it is inserted therethrough to touch the sheet and mark a line of the adjusted length on the sheet as each tape is restored by movement of said pointer.

10. In a graph indicating device, a series of 20 drums mounted co-axially, a series of thin metal tapes of bent cross section on said drums with two ends of each tape extending therefrom, means for holding one of said tapes against each of said drums so that the two ends of the tape project up vertically from the periphery 25 of the drum, and a set of keys and toothed keysystems thereon, one for each tape, said keys and keysystems being mounted in the space between the ends of the tapes and each cooperating with 30 one end of the tape to move the other end to a selected indicating position, and a vertical indicator plate tangent to the front edge of said drums, said other ends of said tapes moving unsupported over said plate.

11. In a graphic counter, a series of thin 35 metallic tapes with a bent cross section, guide rollers, individual coaxially mounted drums around which said tapes are guided and normally formed in J shapes with the lower part of each tape held in contact with 180° of the periphery of a 40 drum by said guide rollers and the one short end and the other long end extending vertically therefrom, a toothed block on the long end of

each tape, a series of keys and attached keysystems formed with ratchet teeth for cooperating with the blocks on the tapes, an adjustable stop common to all the keysystems for limiting the movement thereof when the attached key is depressed to push down the long end and raise the short end of the associated tape, means for restoring depressed keysystems, a fixed vertical indicator plate over which the short ends of the tapes are moved up to indicating positions, means 10 common to all the keysystems for shifting them out of cooperation with the blocks on the tapes, and means adapting the tapes to be restored to normal position.

12. A device of the character described, comprising a board, tapes of the type that may be bent around a support but which are stiff and bar-like when straightened, and means positioned near one edge of the board to support each of the tapes while permitting any desired 20 length thereof to be extended therefrom and be stretched across the face of the board.

13. A device of the character described, comprising a board, supports distributed along an edge of the board with their axes parallel to the 25 plane of the board, and tapes, of the type that are comparatively stiff or rigid and bar-like when straightened, held on said supports and adapted to be drawn therefrom in any desired lengths to be extended across a face of the 30 board.

14. A device of the character described, comprising a board, a series of drums distributed along an edge of the board with their axes parallel to the plane of the board, rollers cooperat- 35 ing with said drums, and tapes, of the type that are comparatively stiff or rigid and bar-like when straightened but which may be bent around part of the periphery of the drums and held thereon by the rollers and drawn therefrom in any de- 40 sired lengths to be extended across the face of the board.

REYNOLD B. JOHNSON.
